Attorney

UNITED STATES PATENT OFFICE.

SAMUEL KOFF, OF NEW YORK, N. Y.

BOX.

Application filed November 19, 1921. Serial No. 516,425.

To all whom it may concern:

Be it known that I, SAMUEL KOFF, a citizen of the United States, residing at New York city, in the county of New York and 5 State of New York, have invented certain new and useful Improvements in Boxes; and I do hereby declare the following to be a full, clear, and exact description of the invention, such as will enable others skilled 10 in the art to which it appertains to make and use the same.

The present invention relates to boxes made of paper, fibre board or corrugated board, and aims to provide a box of novel 15 and improved construction adapted especially for shipping clothes or wearing apparel, without the need of wrapping the box in paper, as usual.

Another object of the invention is the provision of a box comprising tray-like bottom and top sections adapted to telescope or fit 20 together one on the other in a novel manner, and such sections each being formed from a blank and having secure corner constructions to bear together and provide 25 strong corners for the box.

A further object is the provision of novel means for preventing access into the box between the margins of the top and bottom 30 sections for the purpose of withdrawing garments, or the like, from the box, without detection, thus providing assurances against theft while the box is in transit.

As a more specific object, in this connection, the invention aims to provide a 35 stiff lining within one section of the box, composed of corrugated board or the like, and secured to such section, over which lining the other section is telescoped, and 40 whereby the lining stiffens and strengthens the box as well as providing a guard or barrier against access to the contents of the box without the box being opened or so mutilated that the theft would be detected 45 by the receiver.

A still further object is the provision of 50 such a box wherein one section has its edge fitted between the lining and the edge portions of the other section, thereby fitting the sections together in such a way that 55 they cannot be separated for the insertion of the hand or an implement into the box without opening the box or so tearing or mutilating same that the loss or damage could be observed by the person receiving the box.

Another object is the construction of such a box which will afford a saving in material as compared with boxes in which the marginal portions or rims of the trays or 60 sections overlap entirely between the top and bottom of the box, to offset the slight additional expense in securing the lining within one section or tray, and making the cost of manufacture of the improved box about 65 the same or at least not appreciably more expensive than the ordinary telescoped trays, while, at the same time, gaining the advantages hereinbefore indicated.

With the foregoing and other objects in 70 view, which will be apparent as the description proceeds, the invention resides in the construction and arrangement of parts, as hereinafter described and claimed, it being understood that changes can be made 75 within the scope of what is claimed, without departing from the spirit of the invention.

The invention is illustrated in the accompanying drawings, wherein— 80

Figure 1 is a perspective view of the improved box.

Fig. 2 is a perspective view of the top section or cover.

Fig. 3 is a perspective view of the bottom 85 section or body of the box, portions being broken away to show the construction more clearly.

Fig. 4 is a vertical cross section of the 90 box.

Fig. 5 is a plan view of the blank from which the bottom section or tray is folded.

The box is of flat form, such as used for the transportation of cloaks, suits, dresses, furs and other garments or wearing apparel, and the like, and the box is of elongated or rectangular form, as shown, and may be made in any suitable size. The box is composed of two tray-like sections to telescope or fit one on the other, and each section is formed from a blank of paper or fibre board of suitable quality to resist breakage of the box during handling and shipment.

The bottom section or body comprises the bottom 7, side walls 8, and end walls 9, 105 which walls are bent upwardly from the bottom, and said walls are provided at the ends thereof, at the corners of the box section, with the triangular securing flaps 10 and 11, respectively. The flaps 10 of the side walls 110 overlap the end walls on the exterior, whereas the flaps 11 of the end walls overlap the

side walls on the interior, and such flaps are secured to such walls by means of staples 12, or the like, engaging inwardly through such walls and flaps to prevent them from being torn apart without detection. All of the flaps 10 and 11 have edges 18 facing upwardly and located in a common plane parallel with and spaced above the bottom 7.

The top section of cover 13 is of the same construction as above described, and has the rim composed of the side and end walls 14 and 15, respectively. The present box differs from the ordinary telescopic box, wherein the rims or flanges of the trays overlap completely between the top and bottom, because in the present construction, the walls of the sections or trays are only partly overlapped equal to the width of the flaps 16 and 17.

The side and bottom walls of the bottom section have the flaps or extensions 16 and 17, respectively, projecting upwardly therefrom, and of sufficient height to overlap the rim or walls of the top section the desired amount. Such flaps or extensions project upwardly above the edges 12 of the corner securing flaps 10 and 11, so that the flaps 16 and 17 are free and disconnected at their ends or at the corners of the box, thereby permitting the flaps 16 and 17 to be sprung outwardly slightly to receive the top section therein.

The bottom section or body is, in addition to the foregoing construction, provided with means for preventing the insertion of a hand and the withdrawal of a garment or similar article from the box without detection, when the box is tied or bound for transportation. Thus, a lining 19 is disposed within and against the rim or walls of the bottom section, and, as shown, is of corrugated board, with the corrugations extending vertically to strengthen the box at the rim between the top and bottom. The lining may be made of any suitable stiff material, and is of a height equal to that of the walls of the top and bottom sections jointly, not considering the flaps 16 and 17. The lining 19 thus extends above or rises from the bottom section or tray, and the walls 8 and 9 of the bottom section are securely fastened to the lining by means of staples 20, or the like, thereby rigidly securing the rim or walls of the bottom section and lining together, to provide a strong and stiff construction, with the upwardly-extending flaps 16 and 17 loose to be flexed away from the lining for the insertion of the rim or walls of the top section between the lining and said flaps. The flaps 16 and 17, however, are rigidly united with the rim or walls of the bottom section and the material is sufficiently stiff to hold the flaps 16 and 17 against the rim or walls of the top section which can be readily slid or telescoped over the lining 19.

The lining 19 holds the box in form, when it is filled, in order that the top section or tray can be readily slipped over the upper projecting portion of the lining, thereby making the present box more convenient to close than the ordinary telescoping tray box, it being well known that the ordinary tray will bulge out and render it difficult to place the cover thereon, whereas with the present box, the stiff lining will hold its shape with the walls vertical and straight. The top of the top section or tray will seat on the upper edge of the lining, and the edge of the rim or walls will overlap the lining and slip down behind the flaps or extensions 16 and 17 or the bottom section of body, thereby providing an overlap surrounding the lining, which will make it impossible to separate the rims or walls of the two sections or trays for access to the contents. The lining and rim or walls of the bottom section being secured together, will prevent the walls and lining from being separated, and only by tearing the staples loose and tearing or breaking the walls and lining, could access be had into the box, without separating the sections, and such mutilation would have to be such as to be readily observed and detected. Furthermore, the flaps 16 and 17 will hold the rim or walls of the top section against the lining, and will prevent the hand from being inserted between the lining and rim of the top section, although the hand could be inserted between the extensions and top section which would be of no avail.

Another advantage of the present construction resides in the fact that the corner portions of the top section or tray seat on the upper edges of the corner flaps 11 of the bottom section or tray. In this way, such flaps 11 provide seats or shoulders on which the end or corner portions of the top section bear, whereby to resist any compressive force or pressure which may tend to crush the corners of the box. This, together with the lining 19 disposed between the top and bottom, will make the box thoroughly strong, to withstand crushing strains or pressures from the top and bottom as well as from the sides.

The rims or walls of the top and bottom sections only extend part way between the top and bottom, thereby effecting a considerable saving in material, as compared with the ordinary tray boxes which have the rims or flanges overlapping completely between the top and bottom. This saving of material will offset the added expense in securing the lining within one section. The lining being of cheaper material than the material from which the sections or trays are made, and being readily secured within the bottom section, will not add any or prohibitive expense in the manufacture of the box.

The present box is therefore particularly suited for the transportation of clothes and other goods, to prevent theft without the same being radially detected, and to also 5 assure of the contents and box not being crushed during handling and conveyance.

Having thus described the invention, what is claimed as new is:—

A box comprising tray-like bottom and 10 top sections, a lining within the rim of the bottom section, and extending above said rim so that the top section fits thereon and

means securing said rim and lining together, said rim having upwardly-extending flaps extending the length of the walls thereof to the corners of the box and disposed at the outer surfaces of said lining, and the rim of the top section passing between said lining and flaps when said top section is fitted over said lining. 15

In testimony whereof I have signed my name to this specification. 20

SAMUEL KOFF.
